(57) CLAIM

The ornamental design for a card holder case, as shown and described.

DESCRIPTION

FIG. 1 is a front perspective view of a card holder case, showing my new design in an open position;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is the card holder case from FIG. 1 shown in a closed position.

The broken lines in the drawings illustrate the portions of the card holder case, which form no part of the claimed design.

1 Claim, 9 Drawing Sheets
